CAN OPENER

William E. Gundelfinger, House Springs, Mo., assignor to
The Dazey Corporation, St. Louis, Mo., a corporation
of Missouri

Application March 25, 1957, Serial No. 45,420

Term of patent 7 years

(Cl. D22—2)

FIG. 1

FIG. 2

FIG. 3

FIG. 4

Fig. 1 is a side elevational view of a can opener, showing my new design;

Fig. 2 is a bottom plan view thereof;

Fig. 3 is an elevational view showing the side opposite to Fig. 1, and

Fig. 4 is a cross sectional view taken at line 4—4 of Fig. 3.

The essential features of my design reside in the portion shown in solid lines on the drawing. The operating crank, support, and certain other operating parts as shown in broken lines in Fig. 1, have been omitted from the other figures for convenience of illustration.

I claim:

The ornamental design for a can opener, as shown and described.
